(57) **CLAIM**

The ornamental design for a slipper as shown and described.

DESCRIPTION

FIG. 1 is a perspective view of a slipper showing my new design;

FIG. 2 is a right-side view thereof;

FIG. 3 is a left-side view thereof;

FIG. 4 is a front view thereof;

FIG. 5 is a rear view thereof;

FIG. 6 is a top view thereof; and,

FIG. 7 is a bottom view thereof.

FIGS. 1-7 depict a right foot slipper of a pair of slippers; a left foot slipper of the pair of slippers, which is a mirror image of the preceding embodiments, is also claimed but not shown.

The broken lines in the drawing represent portions of the right foot slipper that form no part of the claimed design.
